UNITED STATES PATENT OFFICE.

JOSEPH G. F. SQUIRES, OF NEW YORK, N. Y.

VALVE.

1,119,464.

Specification of Letters Patent.

Patented Dec. 1, 1914.

Application filed December 23, 1913. Serial No. 808,324.

To all whom it may concern:

Be it known that I, JOSEPH G. F. SQUIRES, a citizen of the United States, residing at the city of New York, in the borough of 5 Manhattan and State of New York, have invented certain new and useful Improvements in Valves, of which the following is a full, clear, and exact description.

This invention relates to valves and has 10 special reference to rubber ball valves which are used to control the outlet from flush tanks. This style of valve ordinarily consists of a hollow rubber ball having a hemispherical lower half and a somewhat flattened upper half terminating in a neck or nipple on its vertical axis. The ball is carried at the end of a vertical rod that passes into and engages with the nipple whereby the ball may be raised and lowered to and 15 from its valve seat, the seat being formed at the open end of a pipe of comparatively large diameter through which the contents of the tank flows when the ball is lifted. These ball valves are subjected to various 20 strains when in use which eventually cause their destruction in the operation of the valve. When it is adjusted to its closed position, the ball is subjected to a suction which tends to elongate it; the movement of the 25 ball against its seat is more or less violent; the pressure of the body of water in the tank on top of the ball tends to force it through the open end of the outlet pipe and to distort the upper half of the ball; the lateral 30 movements of the stem cause the bending of the neck or nipple of the valve to which the stem is attached.

All of these strains, as stated, eventually result in the destruction or incapacity of the 35 ball and it is the object of my invention to provide a construction of ball valve which will resist these strains and will therefore be of longer life than the ordinary ball valve.

Accordingly, my invention consists in providing a rigid cage within the interior of the ball, which cage consists of a horizontal ring attached to the inner wall of the ball at or about its middle and rigidly connected by means of inclined arms to vertically and 45 diametrically arranged hubs which are mechanically attached respectively to the upper and lower central points of the ball. By means of such a cage the walls of the ball are sustained against vertical contraction or

elongation as well as against horizontal contraction or extension, while the portions of the wall, which contact with the valve seat, are permitted to have their full flexibility and seating qualities. 55

The invention will be described in detail 60 in connection with the accompanying drawing in which—

Figure 1 is a vertical central section of the improved ball valve; Fig. 2 is a horizontal section on line x—x of Fig. 1; Fig. 3 is a 65 plan of one of the reinforcing parts; and Fig. 4 is a detail of a part of the horizontal ring.

The ball 1 is of rubber and of any of the usual shapes, ordinarily having a semi-circular lower half, which engages with the valve seat and a more or less flattened upper half having a central vertical neck or nipple 2. This nipple usually contains a metallic spud 3, having a vertical central threaded 70 passage into which is screwed the end of the rod 4, which serves as the valve stem by which it is raised and lowered. The valve seat is an inclined curved surface 5 formed at the mouth or upper end of a passage 6 75 through which the water rushes when the ball is lifted. Inside of this ball I place a supporting cage consisting of a horizontal ring 7, sets of inclined arms 8 and 9; the spud 3 and the disk or nut 10. The ring 7 is 80 located at the horizontal substantially central plane of the ball and is preferably secured to the wall of the ball in the process of making the latter, the rubber material being forced or permitted to flow around the 85 outer edge and faces of the ring and into 90 perforations 11, shown in Fig. 4. The arms 8 may be three or more in number and are secured at their lower ends at equal distances apart, to the ring 7. From the ring the arms 95 bend inward, preferably out of contact with the wall of the ball and are secured to the spud 3. The spud 3 is firmly anchored in the neck or nipple 2 of the ball by being 100 molded and vulcanized therein. The set of arms 9 are likewise attached to the ring 7, preferably in a staggered relation with the arms 8 and are inclined inward and downward out of contact with the lower half of the wall of the ball and enter and are 105 secured to the small disk or nut 10. The nut 10 is located some distance above the bottom of the ball and the ball is provided with a

perforation 12 through which passes a post 13 having a threaded end adapted to screw into the nut.

The post carries on its outer or lower end, a rigidly attached curved disk 14 shaped to fit the outer surface of the ball, the post being screwed into the nut until the disk rests against the ball. In order to adjust this disk and post in position the disk is provided with two holes 15 on opposite sides of its center for insertion of a spanner wrench. It will be seen that the cage thus formed together with the disk 14 furnishes a rigid support for the walls of the ball which resists all of the strains to which the ball would ordinarily be subjected in use. The elongation which tends to be produced by the suction in the passage when the ball is seated is prevented by the fact that the lower portion of the ball rests upon the disk 14 and that in turn is sustained by the cage and the stem 4.

When the valve is thrown against its seat the lower wall is permitted to move upward as shown in dotted lines and the strain upon the side walls is therefore avoided. As soon as the valve is seated the wall drops back to its normal position. Lateral movement of the stem 4 cannot result in any tilting or bending of the neck 2 with respect to the body of the ball, because such strains would be imparted to the cage and the bending thereby resisted. The downward pressure of the body of water on top of the ball which would have the tendency to crush the ball or to drive the neck downward is resisted by the upper half of the cage. Any lateral pressures around the horizontal diameter of the ball are resisted by the ring. The cage is inserted in the ball during the process of manufacture, the ball being made in two pieces of similar shape to the cover of a baseball, which are placed in the mold surrounding the cage and while the rubber substance is in a plastic condition it is

caused to embrace the ring and the spud in the manner shown, after which the material is vulcanized.

Having described my invention, I claim:

1. The combination with a hollow ball valve of an internal reinforcement therefor consisting of a ring having inclined arms extending therefrom above and below and two hubs arranged respectively above and below the ring to which said arms are attached, which hubs and the ring are mechanically attached to the wall of the ball. 55

2. The combination with a hollow ball valve and a rigid cage located inside of the same, said cage being mechanically connected with the wall of the ball at two points diametrically opposite each other and on an annular line in a plane at right angles to the line connecting said two points. 60

3. The combination with a hollow ball valve having flexible walls and a rigid internal support therefor, said support comprising a nut, and an external support comprising a disk provided with a screw for connecting it with said nut, the nut and disk 70 being separated from each other and the wall of the ball valve having free movement between the nut and disk, substantially as described. 65

4. A ball valve having flexible walls and 75 an internal rigid support, a post extending from said rigid support to the outside of said ball valve, a disk attached to the outer end of said post, and the wall of the ball valve having an orifice of greater diameter 80 than that of the post through which the post passes whereby the wall will have free play along the post. 80

In witness whereof I subscribe my signature, in the presence of two witnesses.

JOSEPH G. F. SQUIRES.
